TIE DEVICE FOR WALL FORMS

Arthur H. Symons, Chicago, Ill.

Application June 24, 1944, Serial No. 541,920

3 Claims. (Cl. 25—131)

1

The present invention relates generally to tie devices. More particularly the invention relates to that type of tie device which is adapted for use in tying together and holding against separation laterally spaced upstanding forms for concrete walls or like structures and as its principal component parts comprises: (1) a combined tie and spreader rod which extends horizontally between the two forms and has one end thereof anchored to one of the forms and its other end provided with a loop at its extremity and arranged so that it extends through a hole in the other form and is disposed adjacent a single reinforcing beam such as a stud or wale on the outer face of said other form; (2) a bracket which fits against the reinforcing beam; and (3) a wedge which is slidably mounted on the bracket, is adapted to extend through the loop on the extremity of said other end of the combined tie and spreader rod, and serves when in place to connect the bracket to the rod and thus maintain said other form in its proper or desired position with respect to the one form.

One object of the invention is to provide a tie device of this type which is an improvement upon, and has certain advantages over, previously designed devices for the same purpose and is characterized by simplicity of design, cheapness of construction and facility of assembly and dismantlement.

Another object of the invention is to provide a tie device of the type under consideration in which the rod has a smooth cylindrical contour directly inwards of the point where it passes through the hole in the form with the reinforcing beam, the loop at the extremity of the end of the rod that extends through said form with the reinforcing beam is closed or complete and the bracket and wedge are so designed and constructed that when the wedge is in place they are locked against longitudinal displacement in either direction relatively to the combined tie and spreader rod.

A further object of the invention is to provide a tie device of the type and character under consideration in which the loop equipped end of the combined tie and spreader rod extends through a transverse aperture in the reinforcing beam and the bracket and wedge are so constructed and arranged that when the wedge is in its operative position wherein it extends through the loop no forces are set up tending to roll or rock the reinforcing beam relatively to the adjacent form.

A still further object of the invention is to provide a tie device which is generally of new and

2

improved construction and effectively and efficiently fulfills its intended purpose.

Other objects of the invention and the various advantages and characteristics of the present tie device will be apparent from a consideration of the following detailed description.

The invention consists in the several novel features which are hereinafter set forth and are more particularly defined by claims at the conclusion hereof.

In the drawings which accompany and form a part of this specification or disclosure and in which like letters and numerals of reference denote or designate corresponding parts throughout the several views:

Figure 1 is a fragmentary perspective view showing a pair of laterally spaced upstanding wall forming forms having applied thereto a tie device embodying the invention;

20 Figure 2 is a perspective view of the bracket of the device, a portion being broken away in order to show the slot through which the loop equipped end of the combined tie and spreader rod extends;

25 Figure 3 is a perspective view of the wedge; Figure 4 is a perspective view of the combined tie and spreader rod;

Figure 5 is a horizontal section showing the device in its operative position; and

30 Figure 6 is a vertical section taken on the line 6—6 of Figure 5 and illustrating in detail the manner in which the wedge coacts with the loop and the bracket so as to lock the bracket against longitudinal displacement in either direction relatively to the combined tie and spreader rod.

35 The tie device which is shown in the drawings constitutes the preferred form or embodiment of the invention. It is adapted for use in connection with a pair of upstanding wall forming forms F and F' and comprises a combined tie and spreader rod 7, a bracket 8 and a wedge 9. The forms are disposed in laterally spaced relation and are adapted to have concrete poured therebetween for wall forming purposes. As well understood in the art, the forms are removed after hardening or setting of the concrete. The form F comprises a comparatively thin flat composite wooden panel f and an exteriorly disposed wooden reinforcing beam f' in the form of a stud or wale. Such beam extends horizontally, as shown in Figure 1. It serves not only to reinforce the panel f but also to align the planks thereof and is suitably secured by nails or other attaching devices (not shown) to the outer face

40 of said panel f.

50

55

The combined tie and spreader rod 7 extends horizontally between the two forms F and F¹ and is circular in cross section. It is disposed at right angles to the forms and has one end thereof extending through the form F¹ and anchored to the latter in any suitable manner. The other end of the rod extends through a hole f³ in the panel f and a horizontal transversely extending aperture f⁴ in the reenforcing beam f¹. The outer extremity of the end of the combined tie and spreader rod 7 that projects through the aforementioned hole and aperture projects a comparatively small distance beyond the outer face of the reenforcing beam and is bent or shaped to form a loop 10. The end of the loop is welded as at 11 to the adjacent portion of the rod in order that the loop is complete or fully closed. The aperture f⁴ in the reenforcing beam f¹ is in alignment or registering relation with the hole f³ in the panel f. The aperture and hole are of sufficient width to permit the closed loop 10 to pass therethrough in connection with assembly of the combined tie and spreader rod 7 with respect to the form F. The portion of the rod that is directly inwards of the hole f³ in the panel f has a smooth cylindrical contour and possesses no enlargement, washer or crosspin in abutment with the inner face of the panel f.

The bracket 8 is in the form of a plate metal stamping and fits against the outer face of the reenforcing beam f¹. It is horizontally elongated and consists of a flat intermediate wall 12 and a pair of vertically spaced horizontally extending side walls 13 and 14. The intermediate wall 12 fits flatly against the outer face of the reenforcing beam f¹ and is fixedly secured in place by way of a pair of lag screws 15. The threaded shanks of the latter extend through horizontally elongated slots 16 in the ends of the intermediate wall 12 and project into the outer portion of the reenforcing beam. The central portion of the intermediate wall 12 of the bracket is provided with a horizontally elongated slot 17 which is in registry with the outer end of the transverse aperture f⁴ in the reenforcing beam f¹ and has the loop 10 of the rod 7 projecting therethrough. When the device is assembled the loop 10, as shown in Figures 1, 5 and 6, is disposed horizontally and projects through and outwards of the horizontal slot 17 in the central portion of the intermediate wall 12 of the bracket. The bracket side wall 13 is formed integrally with, and projects outwards from, the upper margin of the intermediate wall 12 and the bracket side wall 14 is formed integrally with, and projects outwards from, the lower margin of said intermediate wall. The central portion of the side wall 13 is provided with a slot 18 and this extends at right angles to the intermediate wall 12 and is vertically aligned with the central portion of the loop receiving slot 17 in the intermediate wall. The central portion of the side wall 14 of the bracket is provided with a slot 19 and this extends parallel to, and is in vertical alignment with, the slot 18 in the central portion of the side wall 13. As best shown in Figure 2, the inner ends of the slots 18 and 19 terminate adjacent the outer face of the intermediate wall 12 of the bracket.

The wedge 9 is stamped from flat plate metal and is mounted for vertical sliding movement in the slots 18 and 19. It is preferably arranged so that the small end thereof projects downwards. The slots 18 and 19 are of such length that when the wedge 9 is driven downwards the upper end of the wedge fits snugly in the slot 18 and the

lower end of the wedge fits snugly in the slot 19. The central portion of the wedge is adapted to extend through the loop 10 on the end of the combined tie and spreader rod that projects through the panel and reenforcing beam constituting the form F and is so dimensioned or proportioned that when the wedge is driven downwards into its operative position it fits snugly in the loop 10. When the wedge is in place the bracket and wedge are locked against longitudinal displacement in either direction relatively to the combined tie and spreader rod and hence they, together with the rod, hold the form F in fixed spaced relation with the form F¹. By reason of the fact that the loop equipped end of the rod 7 extends through the transversely disposed aperture f⁴ in the reenforcing beam f¹ the forces which result from driving of the wedge 9 into its operative position do not tend to roll or rock the beam relatively to the panel f. When it is desired to remove the form F the wedge 9 is driven upwards until it is disengaged from the loop 10. In order to maintain the wedge in slidably connected relation with the upper side wall of the bracket, i. e., the side wall 13, the lower end of the wedge is provided with a crosspin 20. The length of this pin is slightly greater than the width of the slot 18 with the result that the wedge is permanently retained in connected relation with the upper side wall 13. The width of the slot 19 and the width of the space within the loop 10 are such that the pin is free to pass through said slot 19 and the loop when the wedge is shifted upwards in connection with release thereof from the loop.

When it is desired to use the tie device the form F¹ is first erected or properly positioned and the adjacent end of the combined tie and spreader rod 7 is anchored thereto. Thereafter the form F is positioned in opposed relation with the form F¹ and is manipulated so as to position the hole f³ in the panel f in registry with the loop 10 of the rod 7. After such manipulation of the form F such form is shifted bodily towards the form F¹ until the loop 10 is disposed directly outwards of the horizontal slot 17 in the central portion of the intermediate wall 12 of the bracket. In connection with inward shift of the form F the wedge 9 is held so that the small or lower end thereof is above the slot 17. After proper positioning of the form F the wedge 9 is driven downwards so as to bring the central portion thereof into seated relation with the loop 10 and its lower end in seated relation with the slot 19 in the lower side wall 14 of the bracket. As heretofore pointed out, when the wedge is driven into its operative position the upper portion thereof fits snugly in the slot 18, the central portion fits snugly in the loop 10, and the lower end fits snugly in the slot 19. When the device is fully assembled the form F is locked or held against longitudinal displacement in either direction relatively to the combined tie and spreader rod 7. After assembly of the device concrete is poured into the space between the two forms. After hardening or setting of the concrete the forms are removed from the concrete formed wall. In connection with removal of the form F the wedge 9 is driven upwards until it is disengaged from the loop 10. Thereafter the form F¹ is shifted laterally away from the wall. After removal of the form F the end portion of the rod 7 having the loop 10 is severed from the central portion of the rod which is embedded in the wall.

The herein described tie device effectively and

efficiently fulfills its intended purpose and may be assembled and dismantled with facility. It is essentially simple in design and construction and hence may be manufactured at a low and reasonable cost. By reason of the fact that the loop at the end of the rod is closed or complete and the wedge, when it is in its operative position, fits snugly in the loop and the bracket there can be no slippage whatsoever of the form F with respect to the rod. The device is adapted or designed to be used with like devices in holding the two forms against separation during a concrete pouring operation. Whereas the device has been described as comprising a single bracket and a single wedge at one end of the combined tie and spreader rod it is to be understood that in practice the other end of the rod may be connected to the form F' by providing said other end of the rod with a closed loop and utilizing in connection with such loop another bracket and another wedge, as shown in Figures 1 and 5. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. The combination with a wall forming form with an opening therethrough, of a combined tie and spreader rod having one end thereof extending through the opening and provided at its extremity and adjacent the outer face of the form with a completely and permanently closed loop, a bracket of U-shaped cross section connected fixedly to the outer face of the form at a point adjacent the opening and embodying a flat intermediate wall fitting against said outer face of the form and provided with a loop receiving opening in alignment with the opening in the form and a pair of opposed laterally spaced outwardly projecting side walls connected to opposite margins of the intermediate wall and provided with aligned transverse slots, and a wedge shaped plate mounted for longitudinal sliding movement in the slots and adapted to have the portion thereof between the side walls of the bracket fit snugly in the loop so as positively to lock the bracket and form against longitudinal displacement in either direction relatively to the rod.

2. The combination with a wall forming form in the form of a panel and an exteriorly disposed reinforcing beam and with aligned transversely extending openings in the panel and beam, of a combined tie and spreader rod having one end thereof extending through the openings and pro-

vided at its extremity and adjacent the beam with a completely and permanently closed loop, a bracket of U-shaped cross section connected fixedly to the beam at a point adjacent the loop and embodying an intermediate wall fitting flatly against the outer face of the beam and provided with a loop receiving opening in alignment with said openings in the panel and beam, and a pair of opposed laterally spaced side walls connected to opposite margins of the intermediate wall and provided with aligned transversely extending slots, and a wedge shaped plate mounted for longitudinal sliding movement in the slots and adapted to have the portion thereof between the side walls of the bracket fit snugly in the loop so as positively to lock the bracket and form against longitudinal displacement in either direction relatively to the rod.

3. The combination with a wall forming form in the form of a panel and an exteriorly disposed reinforcing beam and with aligned transversely extending openings in the panel and beam, of a combined tie and spreader rod having one end thereof extending through the openings and provided at its extremity and adjacent the outer face of the beam with a completely and permanently closed loop and at the part thereof that is directly inwards of the inner end of the opening in the panel with a smooth or uninterrupted contour free from encumbrances and of less width than the last mentioned opening, a bracket of U-shaped cross section connected fixedly to the beam at a point adjacent the loop and embodying an intermediate wall fitting flatly against the outer face of the beam and provided with a loop receiving opening in alignment with said openings in the panel and beam, and a pair of opposed laterally spaced side walls connected to opposite margins of the intermediate wall and provided with aligned transversely extending slots, and a wedge shaped plate mounted for longitudinal sliding movement in the slots and adapted to have the portion thereof between the side walls of the bracket fit snugly in the loop so as positively to lock the bracket and form against longitudinal displacement in either direction relatively to the rod.

ARTHUR H. SYMONS.
